M. H. Laughridge ATTORNEY.

Patented Sept. 29, 1925.

UNITED STATES PATENT OFFICE.

HARRY S. KIMBALL, OF NEW YORK, N. Y.

ADVERTISING DEVICE.

Application filed April 28, 1925. Serial No. 26,558.

To all whom it may concern:

Be it known that I, HARRY S. KIMBALL, a citizen of the United States, and resident of New York, in the county of New York and State of New York, have invented certain new and useful Improvements in Advertising Devices, of which the following is a specification:

This invention relates to a device for advertising displays and has for an object to provide a cylindrical stand, preferably a simulation of the merchandise advertised which comprises a flat advertising card formed into a cylinder by a band or hoop at top and bottom. In this form the device is vertically stable, readily collapsed or changed and when collapsed occupies a comparatively small space. The invention further resides in the details of construction and arrangement of parts as more fully described in the following specification and shown in the accompanying drawings, in which, Fig. 1 is an elevation of an advertising display constructed according to my invention, Fig. 2 is a modification of the device shown in Fig. 1, Fig. 3 shows one form of display card that may be used with this invention, Fig. 4 is a cross-section showing one arrangement of applying the top and bottom bands, Fig. 5 shows an arrangement of the top and bottom bands in section, alternative to Fig. 4, Fig. 6, shows an arrangement of clamping the card against the bands, Fig. 7 shows the use of a rigid spacer between the top and bottom bands and Fig. 8 is a section detail of Fig. 7.

An effective method of advertising display adapted for store windows and store shelves is an enlarged simulation of the article such, for instance, as a large cylinder or drum for advertising canned goods on which an enlarged label is placed corresponding to the label on the cans. These cylinders or drums take up considerable space and are bulky to transport. In the present invention the same results are secured by using an advertising card similar to what are used in street car displays. These cards are set on their edge in a hoop or circular band at the bottom and are held in place by a similar band at the top, the combination forming a cylinder which is stable about its axis, which is light and portable and when disassembled the card is packed as flat stock and the hoops are placed together thereby economizing space and se-

curing a construction that is comparatively inexpensive.

In the drawings 11 represents a cylindrical advertising device constructed according to my invention in which the display is placed on the cylindrical body 12 which may be formed of flat cardboard stock as indicated in Fig. 3 and the display may be arranged in panels as indicated at 12 and 12^a or in any manner suitable to the article advertised. A hoop or band 13, usually made of rolled metal is provided at the top and a similar band 14 is provided at the bottom. These bands are provided with suitable grooves or cleats, as hereafter described, to engage the edge of the card. The card is rolled in the form of a cylinder and placed in the bottom hoop after which the top hoop is placed on the top edge thereby forming a cylinder which is vertically stable.

The hoops may be variously formed to engage the card. In Fig. 4 the hoops are formed with a continuous groove by the turned over edge 21, the edge of the card 12 being placed in this groove as shown. The bottom groove is formed with a horizontal ridge 23 to form a seating for a circular base 22 which, in case of large light hoops maintains a perfect circle.

In Fig. 5 the hoops are rolled in the form of an angle having a horizontal leg 24. From this leg cleats 25 are punched at intervals which are pressed against the card to hold it in place as indicated in Fig. 7.

In Fig. 6 the bands are formed in a semi-circle as at 26, a wire hoop 27 clamps the card in the semicircular ridge at the top and a similar wire hoop 28 clamps the card at the bottom.

Where the device is comparatively long or the cardboard stock is light it may be desirable to use rigid vertical spaces between the hoops to support the top of the device. This may be secured by the sheet metal spacers as indicated in Fig. 7 in which 31 is a strip of sheet metal engaging the top and bottom hoops and having a turned over edge as at 32 Fig. 8 which clamps the edge of the card. These spacers when used intermediate the ends of the card may be constructed from a plain strip of sheet stock.

In Fig. 1 it will be noted that the card does not pass completely around the cylinder, the spacers 32 marking the limits of the card. In this case the construction readily adapts itself to cards of various

widths and to any length. In Fig. 2 the card makes a complete cylinder the ends being secured along the vertical edge 41. Fasteners of any commercial type may be used, as at 42 to secure the hoops to the card.

Having thus described my invention, I claim:

1. An advertising device as described comprising a display card, a pair of grooved circular bands and rigid spacers of sheet stock, said bands arranged to engage said card at top and bottom in said groove and to engage the ends of said spacers in said groove whereby said device is held rigidly vertical.
2. An advertising device as described

comprising a display card, a pair of circular bands and rigid spacers, said bands arranged to engage said card at top and bottom and to engage the ends of said spacers and said spacers arranged to engage the edge of the said card.

3. An advertising device as described comprising a display card and a pair of circular bands, said bands arranged to engage said card on two parallel edges and independent circular means for stiffening said bands.

Signed at New York, in the county of New York and State of New York, this 16th day of April A. D. 1925.

HARRY S. KIMBALL.
